UNITED STATES PATENT OFFICE.

**THEODORE H. MILLINGTON, OF DETROIT, MICHIGAN, ASSIGNOR OF ONE-HALF TO
DETROIT BODY COMPANY, OF DETROIT, MICHIGAN, A CORPORATION OF MICHIGAN.**

DESIGN FOR AN AUTOMOBILE-BODY.

44,851.

Specification for Design.

Patented Nov. 4, 1913.

Application filed August 21, 1913. Serial No. 786,039. Term of patent 14 years.

To all whom it may concern:

Be it known that I, THEODORE H. MILLINGTON, a citizen of the United States of America, residing at Detroit, in the county of Wayne and State of Michigan, have invented a certain new, original, and ornamental Design for an Automobile-Body, of which the following is a specification, reference being had therein to the accompanying drawings, forming part thereof, in which—

Figure 1 is a side elevation; Fig. 2 is a perspective view; and Fig. 3 is a cross-section.

I claim:

The ornamental design for an automobile body, as shown.

THEODORE H. MILLINGTON.

Witnesses:

W.M. J. BELKNAP,
JAMES P. BARRY.
